United States Patent

Des. 236,454
Patented Aug. 26, 1975

236,454

TIRE

Philip S. Hammond, Akron, and Donald L. Roberts,
Cuyahoga Falls, Ohio, assignors to The Goodyear Tire
& Rubber Company

Filed Sept. 19, 1973, Ser. No. 398,613

Term of patent 14 years

Int. Cl. D12—15

U.S. Cl. D12—147

The figure is a perspective view of a tire showing our new design, it being understood that the design is repeated throughout the circumference of the tire as shown schematically by solid lines, the opposite side being substantially the same as that shown.

We claim:

The ornamental design for a tire, substantially as shown and described.
